UNITED STATES PATENT OFFICE.

SOPHIA ZEUGSCHMIDT, OF PITTSBURG, PENNSYLVANIA.

LEATHER GOODS.

No. 927,761.

Specification of Letters Patent.

Patented July 13, 1909.

Application filed October 26, 1908. Serial No. 459,471.

To all whom it may concern:

Be it known that I, SOPHIA ZEUGSCHMIDT, a citizen of the United States, residing at Pittsburg, in the county of Allegheny and

5 State of Pennsylvania, have invented certain new and useful Improvements in Leather Goods, of which the following is a specification.

The invention has relation to leather bags 10 or pouches, and particularly to that species of bag or pouch commonly known as a chatelaine. The primary object of my invention is the provision of a convenient and accessible receptacle for such articles as are constantly employed by a saleslady, seamstress, 15 or person of like employment, and which must in consequence be always accessible for immediate use. One embodiment of my invention is illustrated in the accompanying drawings, wherein:—

Figure 1 is a front elevation of the chatelaine,

Figure 2 is a rear elevation of the chatelaine,

25 Figure 3 is an end elevation of Figure 1,

Figure 4 is a section on the line IV—IV of Figure 1,

Figure 5 is a section through one of the supporting straps, and

30 Figure 6 is a section through a modified form of supporting strap.

Referring to the drawings it will be seen that my invention resides in the arrangement of the body portion 1 of the chatelaine,

35 and in the details of the suspending or supporting straps 2—2. The chatelaine is of any desired shape and size and is provided in front with two receptacles or pockets 3 and 4, and in back with another such receptacle 5.

40 These pockets 3, 4 and 5 are formed by the flat piece 6 attached to the supporting straps 2—2, by the piece 6', which is a single strip extending entirely around the piece 6, and by the piece 6² attached to the piece 6'. It

45 will be noted that the piece 6 constitutes not only the support for the device but also the dividing wall between the front and rear pockets. The receptacle 3 is, as shown, an open pocket as it is intended for containing

50 shop or clerk books, which are in constant use and which must be readily accessible. The receptacles 4 and 5 are preferably provided with closing flaps and are adapted to contain articles of value such as kerchiefs, spec-

55 tacles, purses and the like. In order that the clerk or saleslady may have a supply of

pins, needles and similar accessories, a pin cushion 7 is provided, preferably attached to the front wall of the pocket 4, as shown in Figures 1, 3 and 4.

60 Referring to the means of suspending the chatelaine (see particularly Figures 1 and 5) it will be seen that the straps 2 are formed of several layers or strips of material 8 and 9, which strips are provided on their front faces with the slots 10—10, and on their rear faces with the slots 11—11, forming with the strips pockets for the reception of such articles as pencils, pins, scissors, rulers and the like. A supplemental strip 12 is attached to the front 65 of the straps 2—2 and is similarly provided with a slot 13. By this arrangement a pocket is formed of such construction that the articles inserted are firmly held by and retained within the walls of the pocket. 70

75 If the articles are of such configuration that they may catch or hook together, or if they are of such a character that they may be injured by contacting upon being inserted into the pocket, it is preferable to provide, 80 as illustrated in Figure 6, a supporting strap composed of three strips, 8', 9' and 14, in which case the middle or central strip 14 constitutes the rear wall of the pockets formed by the strips 8' and 9', and prevents 85 the contacting of the articles inserted therein. A supplemental strip 12 may be also provided in this case, and if desired a similar strip may be attached to the rear faces of the straps. 90

95 It will be observed that by this arrangement of bag and supporting means therefor, there is obtained a very convenient form of chatelaine, which is constructed so as to contain all immediate accessories readily at hand and available for instant use, which also provides a secure and safe retaining means for articles of value, and of which the component parts are simple and easily attached together. It is obvious that it can be applied 100 to a variety of uses and in a great number of employments, and that it may be used equally well if desired for ordinary use. Other advantages will readily occur to those familiar with the art. 105

Having thus described my invention and illustrated its use, what I claim as new and desire to secure by Letters Patent, is the following:

110 1. A chatelaine comprising in combination a bag portion, a multi-piece strap for suspending the bag, said strap being provided

with a slot to form with the pieces of the strap a pocket to hold small articles.

2. A chatelaine comprising in combination a bag portion, a multi-piece strap for suspending the bag, said strap being provided with a plurality of slots on opposite sides of the strap adapted to form with the pieces of the strap pockets for holding small articles.

In testimony whereof I have hereunto signed my name in the presence of the two 10
subscribed witnesses.

SOPHIA ZEUGSCHMIDT.
